UNITED STATES PATENT OFFICE.

WILLIAM MUESER, OF NEW YORK, N. Y.

RESERVOIR AND TANK.

1,138,394.

Specification of Letters Patent.

Patented May 4, 1915.

Application filed September 14, 1911. Serial No. 649,352.

Be it known that I, WILLIAM MUESER, a citizen of the United States, residing in the borough of Bronx, in the county of New York, city and State of New York, have invented certain new and useful Improvements in Reservoirs and Tanks, of which the following is a specification.

This invention relates to tanks and reservoirs, and its novelty consists in the application of a principle not heretofore used in tank and reservoir design, the construction of tanks and reservoirs in accordance with this new principle and the adoption of the various details resulting from the novel construction as is hereinafter pointed out.

Small circular tanks, as built heretofore, have given little trouble, as an ample amount of material could readily be used in the bottom and wall of the tank to take care of the stresses developed by the weight of the fluid stored in the tank, although this result has only been attained by a wasteful use of material.

Large circular tanks, both of steel and reinforced concrete have frequently failed, and are always leaking, usually in the lower part of the circular wall. This is due to their construction being faulty both in principle and detail. The larger the tank the more serious have been these defects, and the greater the waste of material used in trying to overcome the defects.

It has been the practice to make the bottom and the circular wall of tanks, reservoirs or standpipes integral, firmly fastened together, and the larger the tank the greater have been the precautions taken to tie, rivet or bond these two elements together.

My invention provides that the circular wall shall not be united or fastened to the bottom, but that the circular wall shall be disconnected and loose of the bottom, and I thereby solve problems involved, which have heretofore not been clearly understood, or not been solved.

While this invention necessarily also relates to tanks and reservoirs of steel construction, its importance becomes most evident and it is most readily described in connection with a circular reinforced concrete tank or standpipe of magnitude.

Assuming a circular reinforced concrete tank to be 125 feet in diameter and 50 feet

high, filled with water: The water pressure at the bottom of the circular tank would be 55 about

$$50 \times 62.5 = 3125 \text{ pounds}$$

per square foot; therefore, the tension in the circular wall for one foot of height would be 60

$$\frac{3125 \times 125}{2} = 195,312 \text{ pounds.}$$

It is usual to embed rings of steel bars in the concrete wall to take care of this tension. Allowing a tensile stress of 20,000 pounds per square inch of steel, it would require almost 10 square inches of steel to reinforce the circular wall near the bottom for a height of one foot. Since all materials 65 are elastic, and elongate when subjected to tension, the steel bars will also elongate when under tensile stress. The modulus of elasticity of steel is approximately 30,000,000# 70 pounds, and the circular length of each 75 steel bar in a tank 125 feet in diameter, is about 393 feet, and therefore the elongation of each steel bar ring under a stress of 20,000# per square inch will be

$$\frac{393 \times 20,000 \times 12}{30,000,000} = 3.144 \text{ inches.}$$

This increase in length of the steel bar ring, corresponds to an increase in diameter of the ring of

$$\frac{3.144}{3.141} = 1 \text{ inch,}$$

or in other words, it is necessary for the steel bar ring to increase its diameter from 90 125 feet to 125 feet and 1 inch, in order to be strained to the extent of 20,000 pounds per square inch. Since the steel bar rings are embedded in the circular concrete wall, it is therefore equally necessary for this wall 95 to increase its diameter to a like extent. If therefore the bottom is firmly fastened to the circular wall, either one of two things must happen,—the bottom must increase its diameter being pulled outward by the wall, 100 or if the bottom cannot do this due to the weight on it and its friction on foundations, then the circular wall will be shorn off the bottom in its effort to increase the diameter. My invention recognizes these facts by making bottom and wall independent of each 105

other. The bottom sustains the vertical pressure and does not have to expand, the circular wall sustains the horizontal pressure and is allowed to expand and contract in accordance with the pressure exerted. The construction details to waterproof the joint between bottom and wall and to facilitate the sliding of the wall on the bottom by reducing the friction between the two to a minimum are of minor importance and may be varied without departing from the spirit of the invention.

In the drawings Figure 1 is a vertical section of a part of the bottom and circular wall of a reinforced concrete tank of magnitude embodying my invention and showing a number of construction details designed to waterproof not only the joint between wall and bottom but also the wall and bottom themselves, and Fig. 2 is a horizontal section through the same on the plane of the line 2—2 in Fig. 1 and a top plan view of the parts beneath such plane. Fig. 3 is a view in miniature and in elevation of the complete structure. Fig. 4 is a view similar to Fig. 1 of a simplified form of construction embodying my invention; and Fig. 5 is an enlarged detail in vertical section of one end of the base and the foot of the wall.

In the drawings 10 is the bottom or base of the tank made of concrete and reinforced by radial bars 11, and circular bars 12 placed at appropriate intervals in accordance with the strains they are intended to meet. At its outer edge the bottom is increased both in superficial and cross sectional area to form a supplemental extension annulus 13 to support the additional weight due to the wall 40 of the tank, and this is reinforced by radial bars 14 and circular bars 15 if required.

20 is the circular wall preferably tapering from the bottom toward the top and reinforced by circular bars 21 arranged at gradually increasing intervals. L-beams 22 or similar elements of construction are placed at suitable intervals around the wall in order to give it rigidity to support the bars 21 and to distribute possible shearing stresses 50 in the wall itself. This wall 20 rests upon the bottom 10 merely by gravity. As it will move with respect to the supplemental extension annulus 13 on which it directly rests when subjected to the horizontal pressure 55 of the water, an antifriction element may be placed between the two contacting surfaces, for instance, two plates of metal, a lower plate 23 in the wall and an upper plate 16 in the annulus. The construction 60 which I prefer, however, is to insert between these contacting surfaces a layer of relatively soft material, for instance, oiled paper or tarred felt, which will be somewhat readily abraded or sheared so that it will completely fill any crevices which may exist in

these surfaces and serve as a water seal between them. The relative movement of these surfaces is slight and necessarily slow and this layer need not be very thick or very large. The upper surface of the bottom is 70 provided with a layer of suitable waterproofing material 17, for instance, asphalt, and above that there is arranged a lining 18 of any suitable material. A similar sheath 24 of water-proofing is placed against the 75 inner surface of the circular wall 20, and this is likewise provided with a suitable lining 25. In order to allow for expansion and contraction this lining is made in sections, and joints 26 are arranged between 80 these sections, and these may likewise be filled with waterproofing, if desired.

In order to provide for a maximum amount of movement between the bottom of the tank and the circular wall and to insure 85 still further the waterproofing of the joint, the bottom is sloped inwardly at 19 leaving a wedge-shaped depression or gutter between such slope and the lower inner surface of the circular wall. This depression is 90 preferably filled with an elastic plastic material, like coal tar pitch, indicated at 30. This should be applied when hot so that it will be thin and fill every crevice in either surface. An elastic waterseal is thus formed 95 between the bottom and the circular wall. If the material of which this seal is composed should deteriorate in time at places it can at such places be readily renewed at any convenient time when the tank is empty 100 without in the least interfering with the construction of the tank. It is so arranged that the greater the water pressure, the tighter will such seal become, and, as explained above, should a leak occur its location is quickly ascertained and it can at once be repaired.

In Figs. 4 and 5, a much simpler construction than that shown in the other figures is employed. The wall 41 is reinforced by 110 steel rods 42, and the base 40 has an unbroken upper surface. A suitable packing between the base and the wall is employed, but any other desirable means for making the joint water-tight may be used.

In embodying the invention various forms of construction may be employed, and the details may be varied within wide limits without departing from the said invention. The invention is also applicable to tanks and reservoirs made of steel, concrete and various other material.

What I claim as new is:—

1. A tank or reservoir for fluent material, comprising a bottom and a continuous upstanding confining wall mounted on the bottom, the lower edge of said wall being slideable upon the bottom to permit the expansion and contraction of said wall, without injuring it and said bottom, and anti-fric- 125

tion members interposed between the wall and bottom to permit of said expansion and contraction.

2. A tank or reservoir for fluent material, comprising a bottom having a shoulder and a continuous upstanding confining wall mounted on the bottom alongside the shoulder, the lower edge of said wall being movable upon the bottom to permit of its expansion and contraction without injuring it or said bottom, and a seal of substantially permanently plastic material interposed between the inner face of the side wall and the shoulder of the bottom.
- 10 3. A tank or reservoir for fluent material, comprising a bottom having a shoulder and a continuous upstanding confining wall mounted on the bottom alongside the shoulder, the lower edge of said wall being movable upon the bottom to permit of its expansion and contraction without injuring it or said bottom, a seal of substantially permanently plastic material interposed between the inner face of the side wall and the shoulder of the bottom, and anti-friction members interposed between the lower edge of the wall and bottom.
- 15 4. A tank or reservoir for fluent material, comprising a bottom of cementitious material and a continuous upstanding confining wall of cementitious material mounted on the bottom, the lower edge of said wall being slidably upon the bottom to permit the expansion and contraction thereof without injuring it or said bottom, said bottom fur-

thermore having an upstanding continuous shoulder arranged within the confining wall and spaced therefrom, antifriction plates interposed between the lower edge of the wall and the upper face of the bottom, and a seal of pitch-like material interposed between the shoulder of the bottom and the inner face of the wall.

40 5. A tank or reservoir for fluent material, comprising a bottom, a separate wall mounted on the bottom, and a joint between the wall and bottom, including means to facilitate the movement of the wall on the bottom.

45 6. A tank or reservoir for fluent material, comprising a bottom, a separate wall mounted on the bottom, a joint between the wall and bottom, including means that facilitates the movement of the wall on the bottom, and a liquid-proofing seal interposed between the bottom and wall.

50 7. A tank or reservoir for fluent material, comprising a bottom, a substantially cylindrical confining wall mounted on the bottom, a joint between the lower end of the wall and bottom, including means that facilitates the movement of the wall on the bottom at all points, and means for maintaining the joint sealed irrespective of the movement of the wall.

55 In testimony whereof I affix my signature 60 in presence of two witnesses.

65 WILLIAM MUESER.
